UNITED STATES PATENT OFFICE.

EDWIN J. GOULD, OF BOULDER, COLORADO, ASSIGNOR OF ONE-HALF TO THOMAS E. SAWDEY,
OF BOULDER, COLORADO.

CLIPPER-SHARPENING MACHINE.

No. 874,671.

Specification of Letters Patent.

Patented Dec. 24, 1907.

Application filed September 4, 1906. Serial No. 333,246.

To all whom it may concern:

Be it known that I, EDWIN J. GOULD, a citizen of the United States, residing in the city of Boulder, county of Boulder, State of Colorado, have invented a new and useful Clipper-Sharpening Machine, of which the following is a specification.

This invention has reference to improvements in clipper sharpeners, and its object 10 is to provide a simple and efficient means whereby the blades of a clipper of the reciprocating type may be readily sharpened without affecting the true relation of the blades one to the other.

15 The invention comprises essentially a sharpening member with parallel faces, adapted to be introduced between the blades of the clipper so that the blade to be sharpened has a relative reciprocatory movement 20 across the sharpening plate and is at the same time held in true parallelism with the blade which is not at the moment being sharpened. When one blade has been duly sharpened the sharpening plate is removed 25 and another plate of similar character is so placed as to have a relative movement with respect to the unsharpened blade, so that the latter is subjected to the sharpening action and is still kept in parallelism with the al- 30 ready sharpened blade.

Since in clippers as ordinarily formed one blade is stationary and the other blade reciprocates over the same, it is customary to use two sharpening plates, one of which is 35 long enough to extend over the stationary blade and is provided with end flanges grasping the sides of the stationary blade so as to be held in immovable relation thereto, while the reciprocating blade is caused to move 40 over the sharpening plate in the same manner that it moves over the fixed blade in the normal operation of the device, and since the two faces of the sharpening plate are made strictly parallel the sharpened edge of the 45 reciprocating blade remains in strict parallelism with the stationary blade. Now, when it is desired to sharpen the stationary blade a sharpening plate of proper length, with its ends upturned to grasp the sides of 50 the reciprocating blade, is introduced between the two blades and then the clippers

are operated in the ordinary manner, causing the sharpening plate to reciprocate over the fixed blade, while the two blades are still maintained in strict parallelism. 55

While not necessarily confined to the use of aluminium as the material of the sharpening plate, still I find that it answers the purpose very satisfactorily.

The invention will be fully understood 60 from the following detailed description, taken in connection with the accompanying drawing forming part of this specification, in which,—

Figure 1 is a plan view of so much of a 65 clipper as is necessary for the understanding of the invention, showing a sharpening plate in operative relation to the reciprocating blade; Fig. 2 is an end view of the structure shown in Fig. 1; Fig. 3 is a similar end view of 70 the structure shown in Fig. 1, but with a sharpening plate adapted to operate on the fixed blade; and Figs. 4 and 5 are perspective views of the sharpening plates.

Referring to the drawings, there is shown 75 a clipper body 1 which may be taken as typical of a hair clipper of any style wherein there is a stationary comb blade 2 and a reciprocating cutting or shear blade 3 of the multi-tooth type. The blade 2 is secured to 80 the body 1 by means of a bolt 4 and thumb-nut 5 with an interposed spring 6, all in the usual manner, while the reciprocating blade 3 is held between the fixed blade 2 and the body 1 and is caused to reciprocate by suitable mechanism which for the purposes of the present invention it is not necessary either to show or describe, since such mechanism forms no part of the present invention and may be of any well known construction. 85 It is, of course, necessary that clippers of this type should be kept in a high state of sharpness, so that their cutting edges act as readily as the cutting edge of a razor blade. The action, however, of these clipper devices is similar to that of a shear; in other words, the cut is a shear cut. It is therefore necessary that the coacting faces of the stationary and reciprocating cutters should be always in exact parallelism and in 95 contact at all points along the shear edges. When such blades are removed from the 100

body of the device and are ground separately upon a stone or other means of sharpening it is a difficult matter to maintain the parallelism of the cutting edges of the blades 5 so that when again assembled all parts of the shearing edges of the blades will coact at all times. In order to avoid this difficulty and to prevent any danger of destroying the proper relation between the blades, there is 10 provided by the present invention sharpening plates having their faces parallel and arranged to be introduced between the fixed and movable blades, which are purposely separated to receive such plates. Under 15 these conditions the two blades are held in the same relation one to the other, except for their separation, necessary for the introduction of the sharpening plate, that they have when in use. The consequence is that 20 when being sharpened the parallelism of the cutting portions of the blades is not in any wise disturbed and when the blades are again brought into operative relation one to the other their cutting portions still coact in the 25 same manner in which they did before the sharpening plate was introduced.

In order to provide for the sharpening of both blades under the conditions mentioned there are provided two sharpening plates 7 30 and 8, shown separately in Figs. 4 and 5 respectively. These plates are made sufficiently wide to correspond to the depth of the reciprocating blade 3 from the toothed end to the back of said blade, so that when 35 introduced between the blades the sharpening plate will have the same support on the fixed blade that is provided for the reciprocating blade. At each end each plate 7 and 8 is provided with flanges 9 extending from 40 one face thereof at right angles to such face, while the other face, which, as will presently appear, constitutes the sharpening face, is left perfectly plain without projection. The plate 7 is provided with a central through 45 perforation 10, circular in outline, while the plate 8 is provided with a central through perforation 11, elliptical in outline or, more properly, in the form of a slot the long diameter of which is lengthwise of the plate.

50 The plate 7 is of such length that when placed upon the stationary blade 2 its flanges 9 will embrace the two sides of the stationary blade, as indicated in Figs. 1 and 2, and the hole or perforation 10 is in place to receive 55 the bolt 4. When the plate 7 has been placed as described the blade 3 is then placed upon the upper surface thereof and the body of the clipper is applied and the whole structure is held together by the nut 5 the same as though 60 the clipper were to be used for cutting hair. Now, by operating the clipper in the same manner as though it were in normal operation the blade 3 is caused to reciprocate over

the surface of the sharpening plate 7 with such pressure as may be applied by the nut 5 bearing upon the spring 6. Since the two surfaces of the plate 7 are in parallelism and the plate is so made as to lie truly upon the fixed blade 2, the reciprocating blade 3 is acted upon by the plate in such manner as 70 to be sharpened thereby and still retain the same relation to the cutting face of the fixed blade that it had before sharpening. In other words, the strict relation of the cutting faces of the two blades is in no wise disturbed 75 by the introduction of the sharpening plate 7.

When the reciprocating blade has been suitably sharpened the plate 7 is removed and the plate 8 is placed between the blades. This plate, however, is shorter than the plate 80 7 so that the flanges 9 embrace the sides of the reciprocating blade 3, while the bolt 4 passes through the elongated slot 11. Now, when the clipper is operated after the manner of its normal operation the plate 8 is constrained to move with the blade 3, and, consequently, acts upon the lower blade 2 to sharpen the same, but the parallelism of the blades is still maintained because the faces of the plate 8 are perfectly flat and parallel. 90 Assuming, now, that the sharpening action on each blade has been sufficient, the two blades and the other parts of the clipping device are again assembled, so that the newly sharpened edges are brought into proper relation for cutting. It will be found that these edges have the same true area of contact that they had when first constructed and assembled, and that aside from the fact that the cutting edges have been sharpened 100 and therefore act with increased ease, the operation of the device is the same as it was before the blades were sharpened. In other words, the sharpening of the blades has not in any manner impaired the operation of the 105 clipper, as is so often the case when the blades are removed from a clipper and separately sharpened and then again assembled.

In the practical embodiment of my invention it is, broadly speaking, immaterial what 110 substance the plates 7 and 8 are made of, but I have found that aluminium gives most excellent results, and, therefore, prefer that said plates be made of aluminium.

I claim:—

1. A sharpening means for clippers having parallel blades consisting of a plate having parallel faces and end flanges, one of the faces being adapted to lie against the cutting face of one of the blades with the end flanges embracing the sides of said blades to prevent movement of the plate with relation to said blade and with the other face engaging and relatively movable over the cutting face of the other blade. 120

2. A sharpening means for clippers having

parallel blades consisting of an aluminium plate having parallel faces adapted to lie between the cutting faces of the blades of the clipper when the blades are still assembled but separated sufficient for the purpose, said plate being provided with means for holding it in immovable relation to one blade and

in relatively movable relation to the other blade.

Signed this 30th day of August 1906.

EDWIN J. GOULD.

In the presence of—

EDWIN J. INGRAM,
GEORGE T. JONES.
